PROXIMITY SCORING SYSTEM

Robert V. Werner, La Mesa, and William J. Thompson, San Diego, Calif., assignors to Cubic Corporation, San Diego, Calif., a corporation of California
Filed Oct. 13, 1958, Ser. No. 766,999
6 Claims. (Cl. 343—12)

The present invention relates to a proximity scoring system and, more particularly, to an electronic system for presenting an immediate indication whenever a fired missile attains a predetermined slant range from a designated target.

One of the major elements constituting the air defense complex at the present time is the interceptor aircraft carrying air-to-air missiles for potential use against enemy aircraft. Although aircraft-missile launch techniques have been automatized to a considerable extent, superior pilot skill and judgment are still required in the last analysis to attain a reasonably high kill probability. In order for interceptor pilots to attain this needed degree of skill and judgment, considerable practice is required in launching missiles from the interceptor at simulated targets, i.e., towed drones, balloons, etc. An important aspect of this type of practice is to present immediate "feedback" information to the pilot of the results of each firing, that is, whether the minimum distance reached by the missile from the target, termed target miss-distance, was sufficiently small to register as a "kill," based on the type of missile, warhead and assumed target.

Several systems have been employed, and others proposed for acquiring this miss-distance information, but in all cases, considerable time lag ensues between missile firing and subsequent indication of the results to the pilot. Ground-based systems, for example, can simultaneously track the target, the interceptor aircraft and the missile during its flight from the aircraft toward and past the target. However, considerable time is required after firing to compute miss-distance and relay the results of the computation to the pilot. For optimum training, however, it is desirable to give the pilot a much faster indication of the firing results in order that, when he fires again, he will still recall all details of his previous firing attempt. The problem is analogous to a rifle marksman, for example, shooting a series of bullets at a target one day and then being told the history of hits and misses the next day. Learning, under such conditions, would be greatly protracted because of the basic inability to use the immediate results of each firing for corrective purposes on the next firing.

The present system serves to give an immediate indication to the pilot of his firing performance. It includes one electronic unit located in the target and another, extremely simple transponder unit located in the missile. The target-based portion of the present system transmits a carrier signal frequency-modulated by a range signal which is received by the transponder in the missile and returned, at a different carrier frequency, to the target aircraft.

The range signal will experience a phase shift traveling to and from the missile transponder whose magnitude corresponds to twice the distance between missile and target. The originally produced or reference range signal is, within the target-based unit, effectively delayed in phase by being passed through a resolver. Then, the resolver phase-delayed signal is compared with the phase-shifted range signal acquired by demodulating the received carrier signal from the transponder. Now, the resolver shaft position is preset to a value such that the phase shift introduced in the reference signal in passing through it equals a predetermined missile-to-target distance. Then, the phase-delayed reference signal and the distance-

2

delayed or data signal are continuously compared for phase coincidence, and, upon phase coincidence, an indicator, for example, a smoke bomb in the target, is immediately fired to thereby present an obvious, immediate visual indication to the interceptor pilot that the firing succeeded and a score was made. Of course, if no coincidence occurs, denoting that the minimum missile-to-target range exceeded the distance value initially set into the resolver shaft position, then no scoring indication is generated and the pilot, in this case, receives immediate knowledge of a miss.

The description of the signal modulating and demodulating scheme employed by the present system has been deliberately simplified in the over-all system operational description above but, in practice, represents a major improvement over conventional techniques. In particular, a range signal of 2 mc. is phase modulated on the target carrier signal and this same range signal frequency is retransmitted by the transponder but modulated on a different frequency carrier signal. Then, in the target circuitry, a signal produced by a local oscillator, differing in frequency by 10 kc. from the original range signal, is modulated on a carrier signal whose frequency also differs from both of the transmitted and transponder return carrier signals. This local oscillator signal is mixed both with the original and the return modulated carrier signals and the resulting mixture is applied to the input terminal of each of a pair of respective I-F amplifiers.

30 The result of this mixing action will produce an amplitude-modulated signal of 10 kc. superimposed on the two I-F signal envelopes which carry the identical phase information relative to each other as do the original 2-mc. range signals. The 10-kc. signals are then detected 35 by a pair of A-M detectors, and the referenced derived signal is passed through the noted resolver and the data signal is coupled directly to a phase coincidence detector circuit. Then, phase coincidence between the signals will be detected and a signal representing the detection is 40 transmitted to the indicator portion which then yields a visual indication. By employing this particular modulating scheme, narrow I-F bandwidth requirements may be maintained, based on the 10-kc. signal, since the 45 phase information appears in them rather than the 2-mc. signals originally used. Accordingly, the I-F circuit requirements are greatly minimized, and the high accuracy distance information inherent in the 2-mc. signal phase delay is that effectively measured by the system but at the reduced frequency. Hence, circuit simplicity is combined with high accuracy distance measurement capabilities.

50 It is, accordingly, the principal object of the present system to provide a proximity scoring system for missile launching interceptors, where an immediate indication 55 is given the interceptor pilot of the results of each missile firing at a target.

Another object of the present invention is to provide a slant-range measuring system for producing an immediate, positive indication whenever a predetermined slant 60 range between a pair of moving objects is attained.

Still another object of the present invention is to provide an electronic system for measuring phase delay in a signal transmitted between a pair of objects and presenting a positive indication whenever a predetermined 65 phase delay is obtained.

A further object of the present invention is to provide a proximity scoring system capable of presenting a positive indication when a fired missile passes within a predetermined slant range distance from a target by effectively measuring the phase delay incurred in a signal transmitted from the target to the missile and returned.

A still further object of the present invention is to

provide a proximity scoring system which continuously measures the phase delay incurred in a signal transmitted and returned to a target-based system from a missile with a predetermined phase delay representing a predetermined missile-to-target distance, and presenting a positive indication whenever phase coincidence between the two signals occurs.

Other objects, features and attendant advantages of the present invention will become more apparent to those skilled in the art as the following disclosure is set forth, including a detailed description of a preferred embodiment of the invention as illustrated in the accompanying sheets of drawings, in which:

FIGURE 1 is a detailed block diagrammatic representation of the electronic portion of the present system located in the target;

FIGURE 2 is the circuitry in block diagram form of the phase coincidence detector circuit of FIGURE 1; and

FIGURE 3 is a block diagrammatic representation of the electronic portion of the present system located in the missile.

Referring now to the drawings wherein the same circuit elements are given the same numerical designation in the several figures, there is illustrated in FIGURE 1, the electronic portion of the present system located in the target or its immediate vicinity. It includes a transmitter 10 which includes a pair of crystal oscillators 12 and 14 producing output signal frequencies of 265 mc. and 2 mc., respectively, both being applied to the two input terminals of a phase modulator 15. The output signal of phase modulator 15, constituting the output signal of transmitter 10, is applied to an antenna 16 for transmission to another antenna 17, carried by the missile, and connected to the missile transponder 18 whose circuitry is later shown in block diagram form in FIGURE 3. The common line formed by the output terminal of transmitter 10 and antenna 16 is coupled to the input terminal of a 324-mc. passband filter 19 and also to one input terminal of a mixer 20. The output terminal of filter 19 is coupled to one input terminal of another mixer 21.

A local oscillator, indicated at 22, includes a pair of crystal oscillators 23 and 24 producing 288-mc. and 1.99-mc. output signal frequencies, respectively, which are applied to the two input terminals of another phase modulator 25. The output signal of modulator 25, constituting the output signal of oscillator 22, is applied to the other input terminals of each of mixers 20 and 21.

The output signal of mixer 21 is amplified by an I-F amplifier, indicated at 27, having a center frequency of 36 mc., and is then applied through an A-M detector 28 to one input terminal of a phase coincidence detector circuit, indicated at 32, and shown in detail in the following FIGURE 2. An AGC signal is taken from I-F amplifier 27 on a separate line 30, and also applied to phase coincidence detector 32.

The output signal of mixer 20 is fed serially through an I-F amplifier 34, having a center frequency of 23 mc., an A-M detector 35, an amplifier and phase shifter 36, into a resolver 37, shown in block diagrammatic form. The rotor output shaft of resolver 37 is associated with a dial indicator 38, not shown in detail, and is adapted to be manually rotated for purposes to be later explained. The output signal of resolver 37 is applied over conductor 39 to the other input terminal of phase coincidence detector 32.

The output signal from detector 32 is applied over an output conductor 40 to a relay amplifier 41, whose output signal, in turn, is applied to the energizing coil of a relay, shown generally at 42. The movable contact arm of relay 42 is connected to the positive terminal B+ of a source of positive potential, not herein specifically illustrated, and its lower switch point, in turn, is connected to an indicator 43.

In considering the detailed operation of the proximity scoring system according to the present invention, modu-

lator 15 within transmitter 10 serves to phase-modulate the 2-mc. output signal of oscillator 14 on the 265-mc. output signal of oscillator 12. The output phase-modulated signal is routed to antenna 16 for transmission to missile transponder 18. As will be later shown in more detail in FIGURE 3, and described in connection therewith, transponder 18 receives this target-transmitted signal on its associated antenna 17, mixes it with a 59-mc. signal produced by an internal crystal oscillator and retransmits the sum and difference frequency signals back to antenna 16. The signal received from the transponder will include the original 2-mc. modulation component whose phase, however, has undergone a delay corresponding to the total distance traversed during the course of its transmission, that is, the distance from antenna 16 to antenna 17 and back again, or twice the distance between the target and missile. Accordingly, distance information pertaining to the missile-target spacing is found in the phase difference between the 2-mc. modulation component before transmission and after its return from the transponder.

Local oscillator 22 produces a 288-mc. carrier signal phase-modulated by the 1.99-mc. signal of oscillator 24. This local oscillator signal is mixed, by mixer 21, with the transponder return sum-frequency signal of 324 megacycles, previously passed by filter 19. The resulting signal difference frequency of 36 mc., produced by the mixing action, is amplified by I-F amplifier 27.

Now, a unique result is achieved by mixing two carrier signals of different frequencies, the carrier signals, in turn, being modulated by a respective pair of modulating signals whose frequencies also differ from each other. Without resorting to the highly involved mathematical derivation setting forth the results of such a mixing process, it may be stated that the resulting signal will include, besides the usual mixing components, an A-M signal whose frequency corresponds to the difference in frequency between the two original modulating signals. Hence, since the two modulating signals from crystal oscillators 14 and 24 differ by 10 kc, the I-F signal passing through I-F amplifier 27 will contain an A-M signal component of 10 kc.

Now, as may also be shown mathematically, the phase information, produced originally by the target-to-missile travel, contained in the 10-kc. signal is based not on its own wavelength, but rather on the wavelength of the original, modulating signal of 2 megacycles. This particular aspect of the present invention is of considerable importance since, in general, the precision or accuracy to which phase difference measurements may be taken between a pair of signals is a strict function of their basic wavelength accordingly to achieve high accuracy measurements, it is necessary to employ signals to very short wavelength. However, the employment of very short wavelength signals, that is, signals of relatively high frequency, imposes wide bandpass requirements on the I-F amplifier and results in low gain, poor noise characteristics, high complexity, etc.

Accordingly, the transfer of the phase information contained in the 2-mc. modulating signal into the 10-kc. signal is significant from cost, complexity and accuracy standpoints, since the 10-kc. signal phase information may be readily detected to high accuracy, I-F amplifier 27 may be sharply tuned to acquire high gain characteristics with minimum circuit complexity without in any way affecting the 10-kc. A-M signal passing through it.

A-M detector 28 detects the amplitude modulation signal appearing on the I-F signal and applies the resulting 10-kc. data signal to the phase coincidence detector circuit 32. A 10-kc. reference signal, whose phase relates to the originally produced 2-mc. modulating signal, is formed by mixing the 288-mc. modulated carrier signal from local oscillator 22 with the transmitter 10 modulated carrier signal of 265 mc., in mixer 20. The resulting frequency difference signal of 23 mc. is amplified by

I-F amplifier 34 and will contain the 10-*kc*. A-M component in accordance with operation described for I-F amplifier 27. This A-M component is then detected by A-M detector 35 and the detected signal amplified and transformed into +45° and -45° phase leading and lagging signals, respectively, by amplifier and phase shifter 36. These two signals are then applied across the stator windings, not shown, of resolver 37, and the output signal of the resolver will be taken across its rotor windings, preferably connected as a linear phase shifter. The latter type of connection may be made by connecting a series resistor and capacitor across the rotor, the resistor and capacitor having equal values at the 10-*kc*. signal frequency. With the resolver output connected as described, the 10-*kc*. signal appearing at the resistor-capacitor junction will be phase shifted relative to the applied reference signal an amount exactly equal in degrees to the resolver shaft displacement, away from an initial null position.

The purpose of the present system, as stated earlier, is to give a positive indication if and when the missile reaches a predetermined scalar distance or slant range from the target. Now, the phase difference between the 10-*kc*. data signal out of detector 28 and the 10-*kc*. reference signal from detector 35 yields a continuous, direct indication of the distance between the missile and the target, based, as noted earlier, on the phase shift incurred in the 2-*mc*. modulating signal during its travel.

The 2-*mc*. data signal will undergo a complete cycle of phase delay for every 500 feet, its wavelength, traveled. This means, then, ignoring for the moment possible ambiguities, that any distance of the missile from the target up to 250 feet may be indicated by the present system, since the data or 2-*mc*. signal must travel to the transponder and return. The desired distance indication is accomplished by rotating the shaft 38 of resolver 37 until the phase of the reference signal passing through the resolver is delayed an amount equal to the same delay the data will undergo when the target-to-missile separation equals the desired distance. It will be appreciated that a scale, marked directly in feet, may be associated with shaft 38.

Accordingly, when the desired distance is reached, the data signal and the reference signal, as delayed through the resolver, will have an identical phase and phase coincidence detector circuit 32 will respond to their phase coincidence by applying an output signal to relay amplifier 41. Relay amplifier 41 will then act to operate relay 42 and thereby couple the positive potential appearing on the B+ terminal to indicator 43.

Indicator 43 may be any one of a number of devices capable of giving a relatively instantaneous indication that the preset range distance from the target was attained by the missile. For example, it may be a large flash bulb, smoke bomb, flare, etc., or other type of visual indicator. As will be appreciated, the B+ potential will, in most circumstances, be applied to a suitable triggering device capable of setting off the main indicating chemical or mechanism.

Referring now to FIGURE 2, there is shown phase coincidence detector 32 in detailed block diagrammatic form. In particular, conductor 33 coming from A-M detector 28, not again shown, is applied to the input terminal of a squaring circuit 44, whose output signal is passed serially through a differentiating circuit 45 to the input terminal of a .2-microsecond delay multivibrator circuit 46, the output signal of which is applied to one input terminal of a pulse coincidence circuit 47. In the same way, the output signal from resolver 37, not again illustrated, appearing on conductor 39, is applied serially through a squaring circuit 48, a differentiating circuit 49, through a 25-microsecond delay multivibrator 50 to the other input terminal of pulse coincidence circuit 47.

The output signal of coincidence circuit 47 is applied to the input terminal of a 5-microsecond delay multivibrator

52, whose output signal, in turn, is applied to one input terminal of an "and" circuit 53. The AGC signal of I-F amplifier 27 of FIGURE 1, appearing on conductor 30 is applied to the other input terminal of "and" circuit 53 and the output signal of circuit 53 is applied to the input terminal of a 1-second delay multivibrator 54. The delay multivibrator 54 output signal appears on conductor 40 for application, as before illustrated in FIGURE 1, to relay amplifier 41.

10 Consider now the operation of this FIGURE 2 phase coincidence detector circuit. The input signals appearing on input conductors 33 and 38 from detector 28 and resolver 36, respectively, will be of sine wave configuration and have a frequency of 10 *kc*. Squaring circuits 44 and 48, which, for example may be overdriven class C amplifiers, serve to transform the input sine waves into square wave form, whose leading and lagging edges, in turn, are differentiated by differentiating circuits 45 and 49. The .2-microsecond delay multivibrator 46 responds to each positive pulse, for example, appearing in the output signal of differentiating circuit 45 to produce positive-going signals having a duration of .2-microsecond. In the same way, delay multivibrator 50 responds to each positive pulse in the output signal of differentiating circuit 49 to produce a high voltage level of a 25-microsecond duration.

15 The reason for employing different multivibrator delay times in the two channels is to insure pulse coincidence detection, since the relative missile-to-target velocity will introduce rapidly changing phase shift, i.e., Doppler effect, between the data and reference signals. Accordingly, if pulses of extremely short duration, say of a .2-microsecond period, appeared on both lines, a possibility would exist that the pulses might slip past each other, between cycles, 20 without the occurrence of an exact coincidence. Accordingly, this type of erroneous operation is eliminated by making the reference pulses sufficiently broad that coincidence will occur even under the most extreme relative velocity conditions and will accordingly be detected, in 25 a manner to be shortly shown.

30 35 40 Pulse coincidence circuit 47, operating essentially as an "and" logic circuit, as known in the digital computer art, produces an output signal only when two output signals appear simultaneously from multivibrators 46 and 50. The duration of its output signal, upon input signal coincidence, will therefore correspond to the duration of the shortest, or .2-microsecond signal.

45 50 55 Since the leading and trailing edges of the square wave signals produced by squaring circuits 44 and 48 correspond to zero cross-over points in their associated input sine wave signals, the pulses in the differentiated signals produced by differentiating circuits 45 and 49 will also correspond to the same zero cross-over points. Consequently, the positive-going signals produced by delay multivibrators 46 and 50 will correspond to the zero cross-over points made by their respective channel input signals, and, specifically will correspond to cross-overs made as its corresponding input sine wave goes from a negative to a positive polarity. This is true since the delay multivibrators, as specified, are designed to respond only to the 60 pulses of positive polarity appearing in the pulse stream produced by its associated differentiating circuit.

65 70 75 Coincidence, therefore, between the signals produced by this pair of multivibrators signifies that coincidence occurs between the negative-to-positive zero cross-overs of their respective input signals, as taken from A-M detector 28 and resolver 36, in FIGURE 1. Accordingly, coincidence detection signifies equal phases between the data signal carrying range information between target and missile and the reference signal as delayed by an amount corresponding to the preset position of resolver 36. Hence, at coincidence, the slant range between missile and target equals the predetermined range initially placed in the resolver shaft position, and the out- put pulse resulting from coincidence detection, of .2-

microsecond duration, is applied to delay multivibrator 52, and its period is increased thereby to 5 microseconds.

The 5-microsecond output signal is then applied to "and" circuit 52 along with the AGC signal from I-F amplifier 27 in FIGURE 1 in order to eliminate possible range ambiguities. In considering ambiguities, it will be recalled that the 2-mc. signal is capable of measuring unambiguous range out to 250 feet, since 500 feet corresponded to one complete wavelength and its travel includes the distance to and from the missile transponder. However, as will be appreciated, if the missile were located at, say, 350 feet from the target, the same identical phase delay will be exhibited as would be the case at a 100-foot distance, since the additional one-cycle phase delay undergone in the longer distance would not be detectable. The same effect, of course, is present in continuing the example in distances of 600 feet, 850 feet, etc., or integral multiples of the range signal wavelength. Hence, the received signal will always be ambiguous, since there is no way to determine if the phase delay being measured represents true range, or is true range plus an integral number of wavelengths of delay.

However, by sampling the AGC signal from the I-F amplifier and using it as a gating signal, ambiguities may be eliminated, since the return signal strength will decrease rapidly, specifically as the square of the distance between target and missile. Accordingly, the AGC level is set such that the received signal strength from distances over 250 feet will be insufficient to open "and" circuit 53. However, during the final approach to the target, the transponder signal strength will be increased and a sufficiently strong AGC signal produced to operate "and" circuit 53 with the result that whenever pulse coincidence occurs, the resulting output pulse from the coincidence detector will be passed through "and" circuit 53 and trigger the 1-second multivibrator 54. This output signal, in turn, will be of sufficient duration to activate relay amplifier 41 and, in the manner previously described, trigger indicator 43.

In FIGURE 3 is shown the transponder circuitry in block diagrammatic form. The transponder antenna 17 is coupled to a crystal diode mixer 61 which, in turn, receives the output signal of a 59-mc. crystal oscillator 60. The target-transmitted modulated 265-mc. carrier signal is received on antenna 17 and is applied to the mixer, where it is mixed with the 59-mc. signal produced by oscillator 60. The resulting sum and difference frequencies resulting from the mixing action appear on the mixer output line and are reradiated from antenna 17 back to the target antenna. Only the 324-mc. output signal of the mixer, including the range signal modulated on it, is indicated on the drawing, since it is this mixing product signal which is employed by the target circuitry for range detection purposes.

As will be appreciated by those skilled in the art, the particular carrier signal frequencies produced by the target-based transmitter, the local oscillator and the transponder circuitry are strictly a matter of engineering expedience, and other carrier signal frequencies with appropriate I-F amplifier frequencies could have been employed without involving invention and still achieve the results stated. In the same way, the specific range signal frequency of 2 mc. is a matter of engineering choice as other range signal frequencies could be employed as determined by the accuracy requirements of the system. Also, the 10-kc. frequency difference between the transmitter modulating signal and the corresponding local oscillator modulating signal is also a matter of choice, and, as will be appreciated, other frequency difference values could be employed without the involvement of invention and still obtain the A-M signal components having the desired range and reference phase information.

As will also be appreciated, indicator 43, shown in FIGURE 1, may take many forms, and a stepping switch arrangement could be employed with a number of paral-

lel indicators so that a number of serial indications might be made without having to reset the indicating mechanism after each score.

It will also be apparent that numerous modifications and changes may be incorporated in the particular arrangement of circuits constituting the system shown and described, and still accomplish the over-all function set forth without involving invention. It is also apparent that each of the circuits shown in block diagrammatic form, may take any one of many well-known recognized forms as known in the art and shown in numerous handbooks, technical books, etc., without the employment of invention.

It will be appreciated, of course, that the foregoing disclosure relates only to a detailed preferred embodiment of the invention whose spirit and scope of the invention is set forth in the appended claims.

What is claimed is:

1. An electronic system for producing an indication whenever a missile reaches a predetermined slant range from a target vehicle, said system comprising: first means for producing a range signal; means for producing a first carrier signal phase modulated by said range signal; means for transmitting the phase-modulated first carrier signal; means associated with said missile for receiving the transmitted first carrier signal and retransmitting a second carrier signal phase modulated by said range signal; receiving means at said target for receiving the phase-modulated second carrier signal; first modulating means responsive to the phase-modulated first carrier signal for producing a first amplitude-modulated signal whose modulation signal phase corresponds to the phase of the range signal produced by said first means; second modulating means responsive to the signal received from said receiving means for producing a second amplitude-modulated signal whose modulation signal phase corresponds to the phase of the range signal in said received signal; means for shifting the phase of the modulation signal produced by said first modulating means an amount corresponding to said predetermined slant range; and means for producing an output indication when the phase of said phase shifted modulation signal equals the phase of the modulation signal produced by said second modulating means whereby said predetermined slant range is indicated.

2. An electronic system for producing an indication whenever a missile reaches a predetermined slant range from a target vehicle, said system comprising: means for producing a range signal; means for producing a first carrier signal phase-modulated by said range signal; means for transmitting the phase-modulated first carrier signal; means associated with said missile for receiving the transmitted first carrier signal and retransmitting a second carrier signal phase-modulated by said range signal; receiving means at said target for receiving the phase-modulated second carrier signal; means for producing a third carrier signal phase-modulated by a signal differing in frequency by a predetermined amount from said range signal; first mixing means for mixing the phase-modulated first carrier signal with said phase-modulated third carrier signal whereby a first amplitude-modulated signal is produced whose modulation frequency corresponds to said predetermined difference and whose modulation phase corresponds to the phase of said range signal; second mixing means for mixing the phase-modulated second carrier signal with said phase-modulated third carrier signal whereby a second amplitude-modulated signal is produced whose modulation frequency corresponds to said predetermined difference and whose modulation phase corresponds to the range signal in said received signal; first and second detecting means for detecting the amplitude-modulated signals produced by said first and second mixing means, respectively; phase shifting means for shifting the phase of the detected signal produced by said first detecting

means an amount corresponding to said predetermined slant range; phase coincidence detecting means responsive to a phase coincidence between a pair of input signals for producing an output indication representing said coincidence; and means for applying the phase shifted detected signal produced by said phase shifting means and the output signal from said second detecting means to said phase coincidence detector whereby an output indication is produced upon said predetermined slant range being reached between said missile from said target vehicle.

3. An electronic system for producing an indication whenever a predetermined slant range is attained between a missile and a target vehicle, said system comprising: means for producing a first modulating signal of a first modulating signal frequency; means for producing a first carrier signal of a first carrier signal frequency; first modulating means for modulating said first modulating signal on said first carrier signal; transmitting means associated with said target vehicle for transmitting the modulated first carrier signal produced by said first modulating means; transponder means associated with said missile and responsive to the receipt of said modulated first carrier signal for transmitting a second carrier signal of a second carrier frequency modulated by said first modulating signal; receiving means associated with said target vehicle for receiving the modulated second carrier signal; means for producing a second modulating signal of a second modulating signal frequency; means for producing a third carrier signal of a third carrier signal frequency; second modulating means for modulating said second modulating signal on said third carrier signal; first mixing means for mixing the modulated third carrier signal with the modulated first carrier signal whereby a reference amplitude-modulated signal is produced whose modulating frequency corresponds to the difference between said first and second modulating signal frequencies; second mixing means for mixing the modulated second carrier signal from said receiving means with the modulated third carrier whereby a data amplitude-modulated signal is produced whose modulation frequency corresponds to the difference between said first and second modulating signal frequencies and whose phase relationship with said reference modulating signal corresponds to the slant range between said missile and said target vehicle; first and second detecting means for detecting the amplitude-modulated signals produced by said first and second mixing means, respectively; phase shifting means for delaying the

phase of the output signal of said first mixing means an amount corresponding to said predetermined slant range between said target and said missile; phase comparison means for producing an output signal whenever phase coincidence exists between a pair of applied signals; means for applying the output signal produced by said phase shifting means and the detected signal produced by said second detecting means to said phase comparison means whereby an output signal is produced by said phase comparison means whenever phase coincidence occurs between the phase shifted and detected signals; and means responsive to the signal produced by said phase comparison means for producing an indication of said coincidence whereby said predetermined range is indicated.

4. The electronic system according to claim 3 wherein said phase comparison means includes first and second zero signal cross-over detection means associated with said phase shifting means and said second detecting means, respectively, for producing first and second pulse streams corresponding to the zero cross-over points of the corresponding phase shifted and detected signals, respectively, and means responsive to the simultaneous appearance of a pair of pulses in said first and second pulse streams for producing an output signal.

5. The electronic system according to claim 4 wherein said transponder means includes an oscillator producing an output signal whose frequency corresponds to the difference between said first and second carrier signal frequencies, diode mixing means for mixing the modulated first carrier signal with the output signal produced by said oscillator, and means for transmitting the sum and difference signals produced by said diode mixing means.

6. The electronic system according to claim 5, including, in addition, means for inhibiting the operation of said phase comparison means unless the signal received by said receiving means exceeds a predetermined signal strength whereby slant range ambiguities are avoided.
